(57) **CLAIM**

The ornamental design for a solar powered light bar, as shown and described.

DESCRIPTION

FIG. 1 is an isometric view of a solar powered light bar incorporating my new design, wherein the portions illustrated in phantom form no part of the claimed design;

FIG. 2 is a right side elevation view thereof, wherein the left side elevation view is a mirror image;

FIG. 3 is a top plan view thereof;

FIG. 4 is a front elevation view thereof;

FIG. 5 is a bottom plan view thereof; and,

FIG. 6 is a rear elevation view thereof.
